DESIGN FOR AN AUTOMOBILE RADIATOR ORNAMENT

Harold Brandies, Chicago, Ill.

Application February 28, 1936, Serial No. 61,400

Term of patent 3½ years

To all whom it may concern:

Be it known that I, Harold Brandies, a citizen of the United States of America, residing at Chicago, in the county of Cook and State of Illinois, have invented a new, original, and ornamental Design for Automobile Radiator Ornament, of which the following is a specification, reference being had to the accompanying drawing, forming a part thereof.

Referring to the drawing;

Figure 1 is an elevational view of an auto-

mobile radiator ornament embodying my invention, and;

Figure 2 is a front elevational view of the ornament shown in Figure 1, and viewing Figure 1, from the left;

Figure 3 is a top plan view of the ornament shown in Figure 1.

I claim:

The ornamental design for an automobile radiator ornament, as shown.

HAROLD BRANDIES.
